UNITED STATES PATENT OFFICE.

J. L. MCPHERSON, OF SACRAMENTO CITY, CALIFORNIA.

IMPROVEMENT IN PUMPS.

Specification forming part of Letters Patent No. 35,829, dated July 8, 1862.

To all whom it may concern:

Be it known that I, J. L. MCPHERSON, of Sacramento City, in the county of Sacramento and State of California, have invented a new and Improved Pump; and I do hereby declare that the following is a full, clear, and exact description of the same, reference being had to the accompanying drawings, making a part of this specification, in which—

Figure 1 is a vertical central section of my invention, taken in the line *x x*, Fig. 2; Fig. 2, a horizontal section of the same, taken in the line *y y*, Fig. 1.

Similar letters of reference indicate corresponding parts in the two figures.

The object of this invention is to obtain a pump which may by a very slight manipulation be changed from a force to a lift or suction pump, and vice versa, and also possess the advantage of not being liable to become choked by sand, and by a very simple construction and arrangement of parts have its plunger-rod, an air-chamber, and a buoy combined, so that each of the aforesaid elements will perform its proper function equally as well as if they were applied separately in the ordinary way, thereby not only economizing in the construction of the pump, but also rendering it simple and very efficient in its operation.

To enable those skilled in the art to fully understand and construct my invention, I will proceed to describe it.

The pump-cylinder is made of two parts, A B, the lower part, B, being smaller in diameter than A, and having a cross-bar, *a*, at its lower end, to which a hook may be attached for the purpose of lowering B through A into the well. Packing *b* is interposed between the two parts A B of the cylinder, where they overlap in order to form an air-tight joint, the upper end of B being provided with a flange, *a**, and the lower end of A being of conical form, so that a taper chamber is provided to receive the packing, as shown in Fig. 1. The lower end of the lower part, B, of the pump-cylinder is nearly at the bottom of the well, and the lower part of B is of inverted conical form, as shown at *c*, Fig. 1. Within this part *c* of B there is fitted a box, C, which is also of inverted conical form, corresponding to *c*, but less in diameter, to admit of packing *d* being wound around or adjusted to it.

Within the box C there is permanently secured a central tube, D, of cylindrical form, the upper end of which is nearly on a level with the upper end of the box C. The tube D is equal in diameter to the lower end of the box C, and as the interior as well as the exterior of said box is of conical form, a chamber or space, E, will be allowed all around the tube D between it and the inner side of the box C. The upper end of the tube D forms a seat for a puppet-valve, F, the stem *e* of which works in guides *f f*, formed of cross-bars in the tube D, and a cross-bar, *g*, is attached to the upper end of the box C. The box C is not secured permanently in the lower part of B. It is merely fitted in it, and may be let down therein and removed therefrom when necessary by a hook attached to the cross-bar *g*.

G represents the plunger-box, which is of cylindrical form and of such diameter that it may work freely in B at a point within suction distance of the water. The inner side of the plunger-box G is of inclined or flaring form, gradually inclining outward from its lower to its upper end, and within the plunger-box there is a fixed or permanent central tube, H, the upper end of which is about flush or on a level with the upper end of the plunger-box. The upper end of the tube H serves as a seat for a puppet-valve, I, which works on a vertical bolt, *h*, fitted in a cross-bar, *i*, in the tube H, and in a cross-bar, *j*, in a tube, J. This tube J is considerably less in diameter than the parts A B of the pump-cylinder, and its lower part is expanded in bell form, as shown at *k*, Fig. 1, and perforated with holes *l*, while the part below *k* gradually contracts to form the frustum of an inverted cone, as shown at *m*.

K is a packing, which is of leather or other suitable material. This packing is in the form of a conical ring, and it encompasses the inverted conical lower end, *m*, of the tube J, and is firmly clamped thereto by the plunger-box G and bolt *h*, the nut *h*' of the latter causing the lower part of the packing to be firmly clamped between the inner side of the plunger-box and the inverted conical end *m* of the tube J. The upper part of the packing K works in close contact with the inner side of the part B of the pump-cylinder. The inverted conical lower end, *m*, of the tube J encompasses the tube H of the plunger-box G,

and m is sufficiently larger in diameter than H to admit of a chamber, L , of requisite dimensions being between H and m , as shown in Fig. 1. The tube J extends some distance upward within the part A of the pump-cylinder, and to its upper end there is attached centrally a rod, M , which passes up through a stuffing-box, N , at the top of the part A of the pump-cylinder.

O is a lever, the fulcrum-pin n of which passes through the upper part of a lever, P . The lower end of the lever P is attached by a fulcrum-pin, o , to the outer side of the part A of the pump-cylinder, as shown in Fig. 1. The upper part of the lever P is fitted in a guide, Q , which is attached to the upper part of A of the pump-cylinder, and has a hole, p , made laterally through it to receive a pin, p' , when necessary, said pin when used also passing through the lever P . R is a discharge-spout, which is attached to the part A of the pump-cylinder; and S is a box representing the well or reservoir.

The operation of the pump is as follows: When the device is used as a force-pump, the pin p' is fitted in the lever P above the guide Q , so that the lever P will be left free to move or work on its fulcrum-pin o , and as the lever O is operated or worked up and down a similar or corresponding motion is of course imparted to the tube J . As the tube J rises, the valve F opens and the valve I closes, the water from the well passing up through the tube D and entering the lower part, B , of the pump-cylinder, and when the tube J descends, the valve F closes and valve I opens, allowing the water in B below the plunger-box to pass up through tube H and holes l in J and into B above the plunger-box; and on the succeeding ascent of the tube J and plunger-box water is discharged from the spout R . The tube J serves not only as a part of a plunger-rod, but also as an air-chamber, and causes the water to flow from the spout R in a continuous stream. The tube also serves as a buoy and greatly assists in raising the plunger-box G . The chamber E , which encompasses the tube D , serves to catch all sand and foreign substances which have a greater specific gravity than water, and the chamber L , which encompasses the tube H , performs the same function. These chambers E L effectually prevent the pump, or rather its valves, from becoming choked or clogged with sand or other substances; and when said chambers are filled, the box C and plunger-box G may be very readily removed from the pump-cylinder, the chambers emptied of their contents, and the boxes replaced in the pump-cylinder.

In order to convert the pump into an ordinary lift-pump, the stuffing-box N is detached from the upper end of the upper part, A , of the pump-cylinder and the upper part of the lever P made stationary or fixed by passing the pin p' through the hole p in the guide Q and through the lever P . When the stuffing-box N is removed, there is a double action connected with the part B of the pump-cylinder, as follows: The part B from 1 to 2 is capable of holding just one-half the amount of water that it holds in the same length of stroke below the plunger-box G (say from 3 to 4) after the plunger-box is raised to 2 and 4. Now, suppose the bottom of the plunger to be at 4 and B from 3 to 4, to be filled with water, it will be seen that by lowering the plunger-box to 3 the water will pass through the tube H , and one half will remain in B from 1 to 2, and that the other half will pass out at the spout R , for the simple reason that there is not room for it below (after the pump is once filled.) By then raising the plunger-box G the water from 1 to 2 will be forced upward and out at the spout, and at the same movement the part of B below the plunger-box from 3 to 4 will be again filled by suction or atmospheric pressure. Thus the power is divided between the ascent and the descent of the plunger-box.

Having thus described my invention, what I claim as new, and desire to secure by Letters Patent, is—

1. The movable box C in the lower part, B , of the pump-cylinder, provided with the tube D and valve F , and arranged, as shown, to admit of a chamber, E , around the tube D within box C , as set forth.

2. The central valve-tube, H , in the plunger-box G , in connection with the inner inclined side of the plunger-box and inclined or inverted-cone-shaped end m of the tube J , for the purpose of forming a chamber, L , around tube H , and also for the purpose of securing the packing K to or in the plunger-box, as described.

3. The tube J , arranged and applied to the plunger-box G and within the pump-cylinder, as shown, performing the triple function of a plunger-rod, air-chamber, and buoy, as set forth.

4. The lever P , when arranged, as shown, to be capable of being made fixed or to rock and used in connection with the lever O and tube J , as and for the purpose specified.

J. L. McPHERSON.
